UNITED STATES PATENT OFFICE.

ELLSWORTH R. BATHRICK, OF AKRON, OHIO.

EXERCISING APPARATUS.

1,177,473.

Specification of Letters Patent. Patented Mar. 28, 1916.

Application filed May 8, 1915. Serial No. 26,809.

To all whom it may concern:

Be it known that I, ELLSWORTH R. BATHRICK, a citizen of the United States, residing at Akron, in the county of Summit and State of Ohio, have invented certain new and useful Improvements in Exercising Apparatus, of which the following is a specification.

This invention relates to exercising apparatus, and is designed as an improvement on or development of the exercising apparatus forming the subject-matter of an application for United States Letters Patent, filed by me under date of July 9, 1914, Serial No. 849,950.

The invention disclosed in the application referred to consists in combining with a bedstead, exercising apparatus consisting of horizontal bars, and the present invention utilizes the bed structure of said application as a support for the punching-bag.

The primary object of this invention is to provide a bed structure with a punching-bag exercising device.

The invention further contemplates means for supporting the punching-bag upon a bed so that the bag and its rebound-board may be adjusted both vertically and radially with relation to the bed, to permit the bag to be swung into convenient position for use.

The invention also includes means for securing the exercising device at different adjustments.

The construction of the improvement will be fully described hereinafter, and its features of novelty set forth and defined in the appended claims.

In the drawings:—Figure 1 is a view in perspective of a portion of a bedstead with my improvement applied thereto. Fig. 2 is a detail sectional side elevation of the adjustable supporting means for the punching-bag. Fig. 3 is a detail elevation of a modified form of the invention. Fig. 4 is a detail vertical sectional view illustrating the locking means for the adjustable supporting device for the punching bag, and Fig. 5 is a detail horizontal section of Fig. 4.

The reference numerals 1 and 2 designate the side rails of a bed preferably constructed of metal and connected in the usual manner to the head and foot of the bed, to either of which but generally to the foot portion thereof, my improved exercising device may be secured.

Only one end of the bed structure, the foot portion, is shown in the drawing comprising a transverse bar 3 and two oppositely-curved side supports 4 connected to the bar 3 by parallel vertical bars 5 provided at their upper ends with sleeves 6 through which the curved side supports 4 extend, and at their lower ends with horizontal sleeves 7 through which the transverse bar 3 extends. It will thus be seen that the inner members of each of the pairs of vertical bars 5 are separated, permitting access to the bed between said bars.

The curved side supports 4 are connected at points opposite the ends of the side rails by a truss-rod 8 provided with sleeves 9 to receive the side supports 4 and with sleeves 10 to receive the lower ends of inclined braces 11, the upper ends of which are secured by sockets 12 depending from sleeves 12^a. The sleeves 12^a are horizontally aligned with similar sleeves on the opposite end (not shown) of the bed structure to receive and support horizontal bars 13 adapted to be used for exercising purposes. The construction thus far described is similar to that disclosed in the pending application above referred to. The present improvement is adapted for use in connection with the construction described as well as with any other form of bed structure, the invention involved in this application consisting in adjustably attaching and supporting a punching bag from a bedstead, particularly the foot portion thereof.

Numerals 14 designate a vertically-disposed rotatable standard supported within a sleeve bearing 15 projecting upwardly from one of the sleeves 6 upon the adjacent curved side bar 4. It is to be understood that the term "standard" may include an upright member as a rod or pipe. The upper end of the standard 14 terminates in a right-angular or radially-extending arm 15^a preferably tubular in form to receive an arm 16 adjustably secured to the tubular arm 15^a as by a set screw 17 and having secured to its under side a board 18 serving as a rebound board for a punching bag 19 depending centrally therefrom. The standard 14 is vertically adjustable within its bearing and is adapted to be secured as by a set screw 20.

The standard 14 and its depending punching bag and rebound board are adapted to be radially adjusted and to secure the same in adjusted position any suitable means may

be employed, the means here shown comprising a disk 21 formed with peripheral notches 22, said disk 21 being mounted upon the standard 14, and adapted to be engaged 5 by a spring catch 23 secured at its lower end as by screws 24 to the sleeve 6 or other convenient part of the bed structure. The catch 23 is provided with a lug 25 adapted to engage over the upper surface of the disk 21 10 to hold the latter against upward movement.

The utility and operation of the improved exercising apparatus will be readily understood.

The standard 14 and its angle arm 15^a 15 which support the punching-bag and its rebound board may be readily adjusted to any position convenient to the user with relation to the bed structure and floor space, and as will be apparent, the spring catch is adapted 20 to lock the device in whatever position it may be adjusted to. The standard 14 is also vertically adjustable as already described.

In Fig. 3, a modified construction is shown 25 in which the rotatable standard 14^a is illustrated in connection with a different form of bed structure from that shown in Fig. 1, the modification shewing an ordinary vertical corner post 5^a of tubular construction to receive the vertically-adjustable and ro- 30 tatable standard 14^a. This modified form as well as such other variations and modifications of the invention as may be resorted to without departing from the spirit of the invention as defined by the appended claims 35 is within the scope of the invention.

What I claim as new is:—

1. An exercising device adapted for attachment to a bed comprising a rotatable standard secured to a bed, and capable of 40 vertical adjustment, a punching bag supported by said standard, and means for locking said standard at different radial adjustments consisting of means adjustably fixed to the standard, and a spring latch engag- 45 ing said means to prevent rotary and vertical movement of the standard.

Copies of this patent may be obtained for five cents each, by addressing the "Commissioner of Patents, Washington, D. C."

2. A vertical and rotary adjustable stand- 5 ard adapted to be attached to a bed, a punching bag and rebound board therefor sup- ported by said standard, a locking device 50 for said standard consisting of a notched disk adjustably fixed on said standard, and a catch secured to the bed adapted to engage the disk to prevent rotary and vertical move- 55 ments of the standard.

3. A vertical and rotary adjustable stand- 60 ard adapted to be attached to a bed, a punching bag and rebound board therefor sup- ported by said standard, a locking device for said standard consisting of a notched disk adjustably fixed on said standard, and a catch secured to the bed and adapted to engage the notches of said disk and also to overlie said disk to prevent rotary and ver- 65 tical movements of the standard.

4. An exercising device including a sup- 70 port, a standard loosely mounted in said support, a disk adjustably fixed on said standard and resting on said support, and a catch carried by said support adapted to engage said disk to prevent rotary and vertical movements of the standard.

5. An exercising device including a sup- 75 port, a standard loosely mounted in said support, means for engaging said support for holding the standard in adjusted vertical position, and means co-operating with the aforesaid means for preventing rotary and vertical movements of the standard.

6. An exercising device including a hol- 80 low support, a standard loosely mounted therein, a peripherally notched disk adjust- 85 ably fixed on said standard and resting upon said support, a spring catch engaging the notches in the disk to prevent rotary move- ment of the standard, and a lug carried by the catch overlying the disk to prevent up- 90 ward movement of the standard whereby the same is held stationary.

In testimony whereof I affix my signa- 90 ture.

ELLSWORTH R. BATHRICK.
